UNITED STATES PATENT OFFICE.

EARL R. GASKILL, OF ROYAL OAK, MICHIGAN.

BOOT AND SHOE SHINING DEVICE.

Application filed June 13, 1928. Serial No. 285,082.

This invention relates to shoe polishing devices and has for an object the provision of a device which may be secured to a floor, platform or other stable support, to permit 5 of the brushing or polishing of shoes without requiring the user to bend over or soil his hands, the invention providing means whereby the shoe may be inserted within the polishing device and moved in such manner 10 as to brush or rub all parts of the surface of the shoe, the invention being especially adapted for restoring the shine or polish.

Another object of the invention is the provision of a device of the above character 15 which is resilient, and which is constructed and shaped so as to bear against any part of a shoe.

Another object of the invention is the provision of a shoe polishing device of novel 20 construction having means for mounting the same spaced above a support to provide for the ready insertion and proper movement of a shoe therein, the means for mounting the device and the construction of the polishing 25 element adapting it for shoes of different sizes.

With the above and other objects in view, the invention further includes the following 30 novel features and details of construction, to be hereinafter more fully described, illustrated in the accompanying drawings and pointed out in the appended claims.

In the drawings:—

Figure 1 is a side elevation illustrating 35 the use of the invention.

Figure 2 is a top plan view of the invention.

Figure 3 is a detail perspective view of the resilient frame.

Figure 4 is a like view of one of the anchor 40 brackets.

Figure 5 is a sectional perspective view illustrating a fragmentary portion of one side of the device.

Figure 6 is a detail sectional view taken 45 substantially on the line 6—6 of Figure 2.

Figure 7 is a detail perspective view of one of the attaching plates.

Referring to the drawings in detail where- 50 in like characters of reference denote corresponding parts, the invention as illustrated comprises a frame which is preferably formed of resilient wire and includes spaced upper and lower loops 10 and 11 respectively, the lower loop 11 extending beyond the loop 10 at one end of the frame. Each of these

loops includes substantially parallel side bars 12 and curved connecting portions 13 which connect one end of the side bars, while the opposite ends of the side bars are flared outwardly as shown at 14 and are connected by vertically disposed bars 15. 60

Mounted upon the frame is a polishing element which includes a pocket 16. This pocket extends throughout the length of the 65 polishing element and is adapted to receive the frame as clearly shown in Figures 1, 2, 5 and 6 of the drawings. Secured along opposite edges of the inner wall of the pocket as shown at 17 are the opposite edges of a 70 sheepskin or other polishing strip 18, while a felt or like cushioning pad 19 is interposed between this polishing strip and the adjacent wall of the pocket 16. A soft and yieldable polishing element is thus provided 75 which is mounted upon a resilient frame. By reference to Figure 2 of the drawings it will be seen that the shape of the polishing element is such as to permit of the insertion therein of a shoe, and as the construction described provides a split at one end of the device as indicated at 20, the opposite side walls may be spread to accommodate shoes of different widths. 80

The polishing element is designed to be 85 mounted spaced above a support, such as a floor or other stable member, indicated at 21. For this purpose there is provided anchoring brackets at opposite sides of the device. These brackets each comprise spaced downwardly and outwardly inclined arms 22 whose lower ends are connected by a bar 23, loops 24 being provided at the ends of the bar adjacent the arms 22. These loops provide for the passage of screws or like fastening devices 25. The upper ends of the arms 22 are connected by spring coils 26 with downwardly extending arms 27 and the latter have extending therefrom inwardly disposed rightangular extensions 28. 90 95 100

An attaching plate 29 which is preferably formed of thin metal is provided at opposite ends with sleeve-like extensions 30. These extensions engage around the arms 27 and serve to connect these arms. Struck from the plate 29 are penetrating prongs 31 and these prongs are adapted to be passed through the walls of the pocket 16 and to be bent around the side bars 12 of the frame, as clearly shown in Figure 6 of the drawings. 105 These penetrating points 31 are arranged in upper and lower rows and the outermost 110

penetrating points of the lower row, in addition to engaging the side bars 12 of the frame, also engage the rightangular extensions 28 of the anchoring devices.

5 By reference to Figure 1 of the drawings it will be seen that the polishing device is supported spaced above its support, so that a shoe may be inserted within the polishing element and moved so that the entire 10 surface of the shoe may be rubbed or polished, the resilient character of the frame and the 15 resilient character of the supports acting to insure proper frictional contact between the polishing element and shoe so that a high 20 polish may be readily obtained. While the invention may be used for the application of an original polish, it is especially designed for removing the dullness from shoes already polished so as to restore the shine or polish 25 and maintain the attractive appearance of the shoes.

The invention is susceptible of various changes in its form, proportions and minor 25 details of construction and the right is herein reserved to make such changes as properly fall within the scope of the appended claims.

Having described the invention what is claimed is:

30 1. A shoe polishing device comprising an elongated polishing element including spaced side walls adapted to receive a shoe between them, resilient brackets, said brackets in-

cluding spaced outwardly and downwardly inclined arms, means at the inner ends of the arms for attachment to the side walls of the polishing element, and means to secure the outer ends of the brackets to a stationary support.

2. A shoe polishing device comprising an elongated polishing element including spaced side walls adapted to receive a shoe between them, resilient brackets, said brackets including spaced outwardly downwardly inclined arms, means at the outer ends of the arms to secure the latter to a support, plates secured to and connecting the inner ends of the arms, and means to secure the plates to the side walls of the polishing element.

3. A shoe polishing device comprising an elongated frame including spaced upper and lower elongated loops connected at one end, a cover for said frame, a polishing element located upon the inner wall of the cover, anchoring brackets at opposite sides of the frame, and means to secure the anchoring brackets to the cover and frame.

4. In a shoe polishing device, an elongated resiliently mounted polishing element including spaced side walls, a closed inclined curved end wall, a curved split end wall, and means to secure the polishing element in spaced relation above a support.

In testimony whereof I affix my signature.
EARL R. GASKILL.
